Inventor

UNITED STATES PATENT OFFICE.

THOMAS KELLY GODBEY, OF WALDO, FLORIDA.

CULTIVATOR-TOOTH.

SPECIFICATION forming part of Letters Patent No. 424,973, dated April 8, 1890.

Application filed July 16, 1889. Serial No. 317,676. (No model.)

To all whom it may concern:

Be it known that I, THOMAS KELLY GODBEY, a citizen of the United States, residing at Waldo, in the county of Alachua and State 5 of Florida, have invented a new and useful Cultivator-Tooth, of which the following is a specification.

My invention relates to improvements in cultivator-teeth; and it consists in certain 10 novel features hereinafter described and claimed.

In the accompanying drawings, Figure 1 is a side view of my improved cultivator-tooth. Fig. 2 is a rear view of the same. Fig. 3 is a 15 horizontal section on the line xx of Fig. 1. Fig. 4 is a front view.

The harrow-beam A may be of any desired construction, and the tooth-securing hooks B are inserted transversely through the beam, 20 as shown, the said hooks being adapted to engage the upper end of the tooth and provided with threaded shanks, on which securing-nuts C are mounted. A clamping-plate D is arranged between the hooks and against 25 the side of the beam, and is provided on its outer side with a series of vertical grooves E, as clearly shown. The upper end of the tooth F is provided on its inner and outer sides with longitudinal vertical ribs G, which 30 are adapted to engage the vertical grooves of the clamping-plate, so as to prevent rotation of the tooth when it is in position. The securing-hooks are tightened in place by turning the securing-nuts home, and thereby 35 serve to clamp the upper end of the tooth against the clamping-plate, with the ribs thereon engaging the grooves of said plate.

It will be seen that the tooth and clamping-plate may be readily exchanged from the 40 outer to the inner side of the beam A, or vice versa, owing to the shank of the tooth being provided with the ribs G on its inner and outer sides and the clamping-plate being detachable. The tooth may also be adjusted to 45 work at any desired angle to the beam. The body of the tooth is substantially L shape, the shank F thereof projecting upward from the upper end of the vertical arm of the same. The lower arm of the tooth extends

rearward and outward, the upper edge being 50 curved on the arc of a circle, while the lower edge extends outward and rearward on very nearly a straight line. This arrangement causes the rear portion of the tooth to assume a convex shape, as shown most clearly 55 in Fig. 2, so as to turn the dirt away from the furrow as the tooth is drawn along.

The harrow provided with my improved teeth is drawn over the ground in the usual manner, and the lower edge of the tooth will 60 take into the ground and turn up the same in the usual manner. As the earth is turned up, the concave outer face of the tooth will throw the same over onto the unplowed ground and away from the furrow, so as to 65 leave a clean open furrow and thoroughly pulverize the earth. It will be observed that my tooth is very simple in its construction and that it can be readily adjusted to run at any angle and to any desired depth. 70

Having thus described my invention, what I claim, and desire to secure by Letters Patent, is—

1. The improved tooth consisting of an L-shaped body provided with a vertical shank 75 and a curved horizontal blade, the upper and lower edges of the blade being of different degrees of curvature, and with a concave or spoon-shaped face extending from the shank, the lower edge of the blade being slightly 80 curved, while the upper edge is curved on the arc of a smaller circle, substantially as set forth.

2. The combination of the beam having 85 transverse perforations, the securing-hooks having threaded shanks, the nuts mounted on the latter, the detachable clamping-plate having vertical grooves in its outer side, and the tooth, the shank of which is provided with vertical ribs on its inner and outer sides, 90 substantially as and for the purpose set forth.

In testimony that I claim the foregoing as my own I have hereto affixed my signature in presence of two witnesses.

THOMAS KELLY GODBEY.
